UNITED STATES PATENT OFFICE

2,451,974

LOCKING LEVER FEEDING MEANS

Harry A. Rau, Baltimore, Md., assignor to Crown Cork Specialty Corporation, Decatur, Ill., a corporation of Illinois

Original application August 3, 1940, Serial No. 350,707. Divided and this application February 27, 1943, Serial No. 477,436

3 Claims. (Cl. 193—40)

1

The present invention relates to a cap forming and assembling machine. The present case is a division of my original application for Locking lever feeding means which issued as Patent No. 2,339,807 on January 25, 1944.

The invention disclosed herein is particularly adapted for use with a machine of the type disclosed in my said patent, viz., a machine for forming from a substantially oval and cupped blank provided with projecting ears a completed cap of the type disclosed in the patent to Carl McQuinn, for Pouring spout and closure, No. 2,126,651, issued August 9, 1938. A completed cap of the above type includes a pivoted locking lever to enable the cap to be firmly clamped upon a container mouth and the present apparatus includes means to assemble such a locking lever with the cap blank.

An object of the invention is to provide various improved means for feeding locking levers to a machine of the above general type.

Other objects and advantages of the invention will be apparent from the following drawings, wherein:

Figure 1 is a vertical sectional view through the locking lever feed chute, the lower portion of the view showing the outer end of the locking lever inserting station.

Figure 2 is a perspective view of the locking lever feed control.

Figure 3 is a disassembled view of the mechanism of Figure 2.

Figure 4 is a transverse vertical sectional view on the line 4—4 of Figure 1, and

Figure 5 is an enlarged diagrammatic view of a portion of Figure 1.

The device of the present invention may be generally described as comprising a supply chute 315 (Figure 1) for the locking levers which is controlled by a gate device 316 (see also Figure 2) to deliver locking levers one at a time to a reciprocable feeding element 317 such as disclosed in my said patent. The feeding element 317 conducts each locking lever to the cap blank which is at that time supported upon the feeding element 317. When the lever is in proper position with respect to the arms of the cap blank these arms are bent inwardly by horizontally reciprocating dies 320.

Referring to Figure 1, the supply chute 315 is suitably supported from the base of the machine and comprises a chute or trough element 315 which, as best shown in Figure 4, is U-shaped in vertical section and includes upstanding walls 326 and 327. Considered longitudinally, the chute 315 disclosed herein comprises an infeed end 328

2

which is inclined downwardly at a sufficient angle to cause the locking levers to slide downwardly along the same and then a more steeply angled middle section 329 and, finally, an outfeed portion 330 which is initially still more steeply inclined than the portion 329, but has its downward end curved so that locking levers will be upright, that is, will lie in a vertical plane, when they move from the same into the reciprocable feeding element 317.

The feed control device 316 is positioned at the lower portion of the middle section 329 of the chute. From the feed control device 316 upwardly to a point a slight distance from the extreme upper end of the chute, the chute side wall 326 is provided with an upstanding plate 333 (Figure 4) fixed to the outer surface of the wall, the plate having an overhanging upper edge 334 spaced a substantial distance above the top edge of chute wall 326. The opposite chute wall 327 has a plate 335 spaced above its top edge, which plate extends inwardly over the chute to a point slightly past the inner surface of chute wall 327. Plate 335 is carried upon suitable brackets as indicated at 336 and the extreme upper end of plate 335 is downwardly inclined toward the upper surface of chute wall 327 as indicated at 335a in Figure 1.

By the above arrangement, an operator may drop locking levers C2 into the upper end of chute 315, it only being necessary for the operator to place the shank of the locking levers downwardly in the chute and with the trunnion portion of the levers nearest the chute wall 326, which wall is innermost with respect to the machine. Locking levers thus placed in the chute will slide downwardly so that their cam portions C11 will ride up the inclined upper end 335a of plate 335 to rest or hang on that plate as shown in Figure 4. The inner surface of the chute wall 327 will then contact with the arched portion C12 of the shank and the hump C13 of the lever will contact with the inner surface of the plate 333. Since each lever is hanging upon the plate 335 by its upper portion, its shank C14 will, by its own weight, swing very slightly in a counterclockwise direction as viewed in Figure 5 so that, as indicated in that figure, the downwardly directed trunnion lug C3 will ride up upon the upwardly directed trunnion lug C3 of the preceding locking lever in the chute. Thus, the adjacent locking levers will have the relationship shown in Figure 5, that is, with each locking lever having its downward trunnion nested above the upper trunnion of the preceding locking lever.

The stop mechanism 316 comprises a pair of horizontal arms 340 and 341, respectively, pro-

vided with depending shanks 342 and 343. These arms are vertically reciprocable in a block structure generally designated by the numeral 344, fixed to the chute 315 adjacent the side wall 327 at the lower end of the middle section 329. The arm 340 is notched at its lower outer edge as indicated at 345 and a similar notch 346 is provided at the lower outer edge of the arm 341. The shank 342 of arm 340 moves in a vertical groove 348 in the downwardly facing wall of the block 344 as indicated in Figure 3, this groove being normally closed by a plate 348a as shown in Figure 2. The arm 340 itself extends along a horizontal groove 347 in the top surface of the block 344. The shank 343 of arm 341 extends downwardly through a groove 349 which faces the chute wall 327, the arm 341 normally being partially within this groove as indicated in Figure 2.

The two arms 340 and 341 are urged to downward positions in block 344 by coil springs 350 connected to the lower ends of their shanks and the arms are automatically raised by the engagement of rocker arms 351 extending in opposite directions from a rock shaft 352, the rocker arms being adapted to have their upper surfaces alternately engage pins 353 projecting from the shanks 342 and 343 as indicated in Figure 3.

As best indicated in Figure 1, the arms 340 and 341 are spaced a sufficient distance apart along the chute 315 to permit a locking lever C2 to be positioned between the same. However, it will be noted that the trunnions C3 of the locking lever may extend beneath the arms 340 and 341 so that actually only the body portion of the locking lever will be positioned between the two arms. In any event, when the lowermost arm 341 is in the downward position illustrated in Figure 1, it will hold the entire line of locking levers against downward movement in the chute 315. However, when the upper arm 340 moves down against the upper surface of the chute and the lower arm 341 rises, the lowermost locking lever C2 will slide down through the section 330 of the chute while arm 340 holds the remaining locking levers against movement. Then when arm 340 rises and arm 341 drops, the line of locking levers will move downwardly to position the lowermost locking lever against arm 341.

The rock shaft 352 which actuates the locking lever gate devices 340 and 341 is operated from the heating device 317, as described and shown in my said patent. In Figure 3, the turning movement thus given the rock shaft 352 has rotated the latter a short distance in the direction of the arrow shown in Figure 3, so that the upper arm 340 of the gate device 316 has been lifted and the lower arm 341 has been permitted to lower by the action of its spring 350. The line of locking levers will thus move down against the lower arm 341.

On subsequent following outward movement of the feed device 317, shaft 352 will be rotated in the direction indicated by the arrow in Figure 2, so that the lower arm 341 of gate device 316 will be raised and the upper arm 340 will be lowered. As a result, the locking lever which has been bearing against the lower arm 341 will slide beneath the latter and down the supply chute 315 onto the fixed jaw 386 of the feed device 317. The remaining locking levers will, of course, be stopped by upper arm 340.

The terminology used in the specification is for the purpose of description and not of limitation, the scope of the invention being set forth in the claims.

5 I claim:

1. In an apparatus for assembling with cap blanks locking levers provided with a shank and a face portion arranged substantially at right angles to said shank, a chute U-shaped in cross-section to provide a vertical groove, said chute including a ledge on one upper edge upon which said face is adapted to hang, said ledge overhanging the vertical groove in the chute, the wall of said chute opposite said ledge being so positioned with respect to said ledge as to hold said face portion on the ledge.

2. In an apparatus for assembling with cap blanks locking levers provided with a shank and a face portion arranged substantially at right angles to said shank, a chute U-shaped in cross-section to provide a vertical groove, said chute including a ledge on one upper edge upon which said face is adapted to hang, said ledge overhanging the vertical groove of the chute, the wall of said chute opposite said ledge being so positioned with respect to said ledge as to hold said face portion on the ledge, said ledge being spaced above said chute throughout the major portion of its length but being inclined toward the chute at its upper and infeed portion.

3. In an apparatus of the class described, an inclined U-shaped chute for articles, said chute having its trough facing upwardly, a pair of elements spaced apart lengthwise of the chute, each of said elements including a horizontal arm extending across and above the trough and a depending arm extending alongside the chute, a block in which said depending arms are vertically slidable, said depending arms being spaced in said block in a direction transversely of said chute, spring means to urge said elements downwardly in said block so that their horizontal arms will be adjacent the trough to hold articles against movement, and rocking means extending between said depending arms to alternately lift said elements so that articles may move beneath their horizontal arms.

Certificate of Correction

October 19, 1948.

Patent No. 2,451,974.

HARRY A. RAU

It is hereby certified that errors appear in the printed specification of the above numbered patent requiring correction as follows:

Column 1, lines 1 and 2, for "cap forming and assembling machine" read *locking lever feeding means*; lines 3 and 4, for "Locking lever feeding means" read *cap forming and assembling machines*; and that the said Letters Patent should be read with these corrections therein that the same may conform to the record of the case in the Patent Office.

Signed and sealed this 3rd day of May, A. D. 1949.
